CLAIM

The ornamental design for a dumpling maker, as shown and described.

DESCRIPTION

FIG. 1 is a front and top perspective view of a dumpling maker, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position; and,

FIG. 10 is an enlarged perspective view of detail "10" identified in FIG. 1.

The dash dot dash lines in FIGS. 1 and 10 are for the purpose of depicting the boundary lines of the enlarged view and form no part of the claimed design.
